CLAIM

The ornamental design for an electric self-balancing vehicle, as shown and described.

DESCRIPTION

FIG. 1 is a top, front, and left side perspective view of an electric self-balancing vehicle showing our new design; FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a front elevational view thereof.

In the drawings, the broken lines are included to show portions of the electric self-balancing vehicle that form no part of the claimed design.
